UNITED STATES PATENT OFFICE.

ROBERT HERZOG, OF BERLIN, GERMANY, ASSIGNOR TO C. LORENZ AKTIENGESELLSCHAFT, OF BERLIN-TEMPELHOF, GERMANY.

ARC GENERATOR.

Application filed December 28, 1925, Serial No. 77,985, and in Germany February 13, 1925.

The present invention relates to the use of electric arcs for generating high frequency oscillations in the employment of which a method is known as disclosed, for example, in my U. S. Patent 1,503,324 having for its object to obtain a uniform burning of the electric arc, and employing in combination with the oscillatory arc circuit and with the arc, a circuit which does not oscillate independently, situated on the high-frequency side of the arc between the arc and the oscillatory arc circuit, a large self-inductance being included in this circuit and a second self-inductance being coupled with the first self-inductance in such a manner that the effect of the first self-inductance upon the oscillatory arc circuit is entirely or substantially neutralized.

There exist, however, as a rule, disturbances superimposed on the arc-light oscillations originating from particles of carbon crumbling off or burned out in the arc and causing interference in receiving sets established in the neighborhood of the transmitter, especially when capacities are connected in parallel with the arc for the purpose of further stabilizing it and increasing its efficiency.

According to the present invention these disturbances are eliminated by shunting a part of the large self-inductance by a capacity. It has been found suitable to connect this capacity in parallel with that part of the self-inductance across which the oscillatory circuit is connected, and according to a further feature of the invention the natural frequency of this capacity together with the portion of the self-inductance in parallel with it is made to correspond with that of the circuit in which the disturbances exist, i. e., the frequency of the circuit formed by the arc, its parallel capacity and the leads to the latter. The accompanying drawing shows diagrammatically an arc generator embodying the invention.

In the arrangement as shown an intermediate circuit is interposed between the arc and the antenna-ground or radiation circuit. A self-inductance L_1' of comparatively large size is connected in series with the electric arc B, another self-inductance L_1'' being connected in parallel to the self-inductance L_1' and the arc. C_1 and C_2 are blocking condensers preventing continuous current supplied at the terminals of the arc

from flowing into the oscillatory arc circuit. C_3 is a capacity shunting the arc and serving as a stabilizing means, as is well known in the art. With regard to all currents which flow parallel through these self-inductances L_1' and L_1'' the total self-inductance is reduced to a very small figure. With regard to all currents which pass through the two self-inductances in series, however, the sum of these self-inductances is a factor which must be considered and controlled. The oscillatory arc circuit is constituted by an inductance coil L_2 in series with the capacity C_5 . The effect of the connection of the elements as set forth is that while the arc is shunted by a very high self-inductance L_1' plus L_1'' , for securing a uniform burning of the arc, this self-inductance in the case of series currents is by properly choosing or intimately coupling the two self-inductances L_1' and L_1'' reduced to a very small figure with respect to or as compared with the currents generated by the arc in the oscillatory circuit L_2-C_5 . An antenna-ground circuit A is inductively coupled to the oscillatory circuit L_2-C_5 to which the produced oscillations are transferred and from which they are radiated for telegraphic purposes.

According to the present invention, however, the disturbances generated by the arc are eliminated, by connecting a capacity C_4 in parallel with the self-inductance L_1' . It has been found suitable that this capacity should form together with a self-inductance L_1' an oscillatory control circuit which does not oscillate independently of and whose natural frequency corresponds approximately to the value of the natural frequency of the oscillatory arc circuit consisting of the arc, the self-inductance L_2 and the stabilizing condenser C_5 in parallel therewith, and the associated leads. This latter frequency generally corresponds to the frequency of the disturbing wave.

The arrangement and the tuning of the capacity C_4 need not necessarily be carried out exactly in the above described manner, but this has been found to be the most efficient means of attaining the desired end.

What I claim is:

1. In an arc generator, an oscillatory circuit tuned to the frequency of the oscillations to be produced and with the arc, a shunt circuit which does not oscillate inde-

pendently of the oscillatory circuit, said shunt circuit being situated on the high-frequency side of said arc between the arc and said oscillatory circuit, a self-inductance included in said shunt circuit, a second self-inductance coupled with said first self-inductance in such a manner that the effect of said first self-inductance upon the oscillatory circuit is entirely or substantially neutralized, and a capacity connected across said first self-inductance.

2. In an arc generator, an oscillatory circuit tuned to the frequency of the oscillations to be produced and with the arc, a shunt circuit which does not oscillate independently of the oscillatory circuit, said shunt circuit being situated on the high-frequency side of said arc between the arc and said oscillatory circuit, a self-inductance included in said shunt circuit, a second self-inductance connected in parallel with said first self-inductance and said arc in such a manner that the effect of said first self-inductance upon the oscillatory circuit is entirely or substantially neutralized, and a capacity connected across said first self-inductance.

3. In an arc generator, an oscillatory circuit tuned to the frequency of the oscillations to be produced and with the arc, a shunt circuit which does not oscillate independently of the oscillatory circuit, said shunt circuit being situated on the high-frequency side of said arc between the arc and said oscillatory circuit, a self-inductance included in said shunt circuit, a second self-inductance coupled with said first self-inductance in such a manner that the effect of said first self-inductance upon the oscillatory circuit is entirely or substantially neutralized, a stabilizing capacity shunting the arc, and a capacity in said shunt circuit and connected across said first self-inductance and effective to give said shunt circuit a natural frequency about equal to that formed by the arc, the said capacity shunting the same and the associated leads.

4. In an arc generator, an oscillatory circuit tuned to the frequency of the oscillations to be produced and with the arc, a shunt circuit which does not oscillate independently of the oscillatory circuit, said shunt circuit being situated on the high-frequency side

of said arc between the arc and said oscillatory circuit, a self-inductance included in said shunt circuit, a second self-inductance connected in parallel with said first self-inductance and said arc in such a manner that the effect of said first self-inductance upon the oscillatory circuit is entirely or substantially neutralized, a stabilizing capacity shunting the arc, and a capacity in said shunt circuit and connected across said first self-inductance and effective to give said shunt circuit a natural frequency about equal to that formed by the arc, the said capacity shunting the same and the associated leads.

5. In an arc generator, an oscillatory circuit tuned to the frequency of the oscillations to be produced and with the arc, a shunt circuit which does not oscillate independently of the oscillatory circuit, said shunt circuit being situated on the high-frequency side of said arc between the arc and said oscillatory circuit, a self-inductance included in said shunt circuit, a second self-inductance coupled with said first self-inductance in such a manner that the effect of said first self-inductance upon the oscillatory circuit is entirely or substantially neutralized, a capacity connected across said first self-inductance, and means to impart the oscillations produced in said oscillatory circuit to an antenna circuit.

6. In an arc generator, an oscillatory circuit tuned to the frequency of the oscillations to be produced and with the arc, a shunt circuit which does not oscillate independently of the oscillatory circuit, said shunt circuit being situated on the high-frequency side of said arc between the arc and said oscillatory circuit, a self-inductance included in said shunt circuit, a second self-inductance connected in parallel with said first self-inductance and said arc in such a manner that the effect of said first self-inductance upon the oscillatory circuit is entirely or substantially neutralized, a capacity connected across said first self-inductance, and means to impart the oscillations produced in said oscillatory circuit to an antenna circuit.

In testimony whereof I have affixed my signature.

ROBERT HERZOG.
